Maurice A. Rice,

INVENTOR

BY *Victor J. Evans*

ATTORNEY

UNITED STATES PATENT OFFICE

MAURICE A. RICE, OF CONCORD, NEW HAMPSHIRE

SKATE SHARPENER

Application filed October 20, 1928, Serial No. 313,867. Renewed January 8, 1931.

This invention relates to sharpeners and its general object is to provide a hand sharpener for skates that is primarily adapted to finish or complete the sharpening of the ice 5 engaging surface of the runner of skates in a manner whereby a perfect skating surface is assured.

Another object of the invention is to provide a hand sharpener for skates that will 10 sharpen the blade of a skate after the same has worn down adjacent to the blade, brace or support.

A further object of the invention is to provide a skate sharpener that has stone for 15 its abrasive element, with guards for the stone and the guards also act as guides during the sharpening operation.

A still further object of the invention is to provide a skate sharpener that is extremely 20 simple in construction, inexpensive to manufacture, easy to use and efficient in operation and service.

This invention also consists in certain other features of construction and in the 25 combination and arrangement of the several parts, to be hereinafter fully described, illustrated in the accompanying drawings and specifically pointed out in the appended claims.

30 In describing my invention in detail, reference will be had to the accompanying drawings wherein like characters denote like or corresponding parts throughout the several views, and in which:

35 Figure 1 is a perspective view illustrating one of the positions in which my sharpener may be used.

Figure 2 is a sectional view taken through the sharpener when in the position as shown 40 in Figure 1.

Figure 3 is a similar view illustrating another sharpening position of the device.

45 Figures 4 and 5 illustrate further positions in which the device may be used.

Referring to the drawings in detail, the letter A indicates an ice skate of a well known construction and B the blade thereof.

While I have illustrated my sharpener in use upon a skate of the type as shown, it will 50 be obvious that it can be used on ice skates

of all types. The blade B has its ice engaging surface formed with a longitudinally disposed groove as will be noted upon inspection of Figures 2 to 5 inclusive.

The sharpener includes a stone 1 that is 55 substantially wedge shape in cross section and has a rounded small edge 2 that is adapted for fitting engagement in the groove of the blade B.

The stone is formed with spaced parallel 60 openings arranged adjacent the top or enlarged edge thereof, and these openings may be reinforced by sleeves if it is found desirable, but in any event pins 3 are passed through the openings and are formed with 65 heads on their opposite ends for the purpose of securing plates 4 to the pins, that not only provide a handle as well as a guard for the stone, but the plates extend for the greatest portion of their lower edges, below the small 70 or lower edge of the stone as suggested in Figure 1 to provide guides. The plates 4 are arranged upon opposite sides of the stone and are loosely mounted on the pins so that 75 they may be moved if desired in a plane as suggested in Figure 3.

The forward corners of the plates 4 are beveled or cut-away, and the lower cut-away portions which for distinction are indicated by the reference numeral 5 provide for the 80 projection of the forward lower edge of the stone beyond the cut-away portions so that when a blade has become worn down to adjacent the brace or support thereof, the projecting portion of the stone will be able to 85 engage the ice engaging surface of the blade as will be apparent.

One of the ends of the stone terminate approximately in alignment with one of the ends of the plates, and these mentioned ends 90 constitute the forward or front end of the device, but it will be noted that the stone is considerably longer than the plates and extends beyond the rear ends thereof for a 95 purpose which will be presently apparent.

From the above description and disclosure of the drawings, it will be obvious that I have provided a sharpener that is primarily designed for finishing and completing the ice engaging surface of the blade of 100

a skate, and due to providing a stone with a rounded lower edge as shown, with the rounded lower edge being of a size to be received in the longitudinally disposed groove 5 of the blade, the sharpener will remove all rough surfaces from the groove as well as from the outer edges thereof when the sharpener is used in the manner as illustrated in Figures 1, 2 and 3.

10 In order to retain the small edge of the stone rounded in cross section as shown, the blade of the skate is reciprocated from its full line position as shown in Figure 3 to its dotted line position, and this sharpening action 15 is made possible by the novel means of securing the plates to the stone.

The rearward projecting end of the stone is primarily used for removing burrs, roughened places and the like upon the opposite 20 sides of the blade adjacent its ice engaging surface, and when this function is accomplished, the sharpener is disposed with respect to the skate blade in the manner as shown in Figures 4 and 5.

25 It is thought from the foregoing description that the advantages and novel features of my invention will be readily apparent.

I desire it to be understood that I may 30 make changes in the construction and in the combination and arrangement of the several parts, provided that such changes fall within the scope of the appended claims.

What I claim is:

1. A sharpener of the character described 35 comprising a stone, plates loosely secured upon opposite sides of said stone to allow swinging movement thereof and terminating below one of the edges of the stone, said plates having one of their lower corners 40 cut-away for disposing a corner of the stone below the cut-away portions.

2. A sharpener of the character described comprising a stone substantially wedge shape in cross section, plates loosely secured 45 to said stone to allow swinging movement thereof and disposed upon opposite sides of the stone and below the same, said plates having the greatest portion of the lower edges disposed below the small edge of said 50 stone, the remaining portion of the lower edges being cut-away for disposing a corner of the stone below the plates, and said stone being of a length for disposing a portion thereof beyond one of the ends of said plates.

35 In testimony whereof I affix my signature.
MAURICE A. RICE.
